UNITED STATES PATENT OFFICE.

CHARLES W. WEILAND, OF BROOKLYN, NEW YORK.
AUTOMATIC SAFETY LAUNCHING DEVICE FOR LIFE-BOATS.

1,104,089.

Specification of Letters Patent.

Patented July 21, 1914.

Application filed December 5, 1913. Serial No. 804,839.

To all whom it may concern:

Be it known that I, CHARLES W. WEILAND, a citizen of the United States, and a resident of the borough of Brooklyn, in the 5 county of Kings and State of New York, have invented certain new and useful Improvements in Automatic Safety Launching Devices for Life-Boats, of which the following is a specification.

10 This invention relates to automatic safety launching devices for life boats.

It is the especial purpose of the invention to prevent the capsizing or crushing of life boats while being launched by the collision of the life boat with the hull of the ship as the ship rolls or pitches on the sea. To accomplish this purpose, I provide the life boat with wheels or rollers located at the proper points to receive the impact of 20 all collisions of said life boats with the side of the ship, and to protect the side of said life boat from being crushed in by the collision; and said wheels or rollers are carried by strong rigid brackets of such form 25 and construction as to distribute the shock of the impact both laterally and fore and aft; said brackets being secured to strong strengthening bands secured on the outside of said life boat from the gunwale to the 30 keel thereof. Thus if the life boat collides with the hull of the ship while being lowered, said life boat rolls unharmed down the hull of the ship in an upright position, and without being capsized by the shock of the 35 collision.

Referring to the drawings which accompany the specification to aid the description, Figure 1 is a broken elevation showing a life boat equipped with my invention and 40 hanging from a davit in a partly lowered position, the aforesaid wheels being just about to collide with the ship's hull; Fig. 2 is an elevation of a life boat equipped with my invention, on a large scale; Fig. 3 is a 45 broken detail view of the said wheel and bracket as seen from the end of the life boat, and Fig. 4 is a view of the said wheel and bracket as they appear when looking toward the rim of said wheel; Fig. 5 is a 50 broken detail of the yoke which carries said wheel.

At suitable positions on the hull of the life boat A, are securely fastened the strengthening metal bands B, one band being located 55 forward and the other aft of the greatest beam of said life boat, and said bands ex-

tend from the gunwale to the keel of said life boat. Adjacent to the curve of the bilge are firmly secured to said bands B, and to the hull of said life boat A, the 60 standards C which carry the wheels H, and which standards are hereinafter collectively termed "brackets," there being two similar brackets and wheels on the side of said life boat which is adjacent to the hull of said 65 ship S.

It is an important and novel feature of my invention that the brackets C are located adjacent to the curve of the bilge of the life boat, and consequently are at or but 70 slightly above the center of gravity of the boat, and thereby avoid the danger of the capsizing of the boat when the wheels H strike against the hull of the ship, which danger is present in all of the devices known 75 to applicant in the art. Said brackets C comprise the yokes c which are securely fastened at their bottoms to said bands B; the longitudinal stay braces e e which hook over the outer ends of said yoke c and are firmly 80 secured at their other ends to the hull of said life boat (Fig. 4); and the lateral stay brace d, located at its upper part between the hooked end of a stay brace e and the hub h of the wheel H, so that said stay brace 85 serves also as a washer to prevent undue lateral motion of said wheel H, the outer ends of said brace d being firmly secured to the said band B by rivets or bolts, through said band B and the hull of said 90 life boat (Fig. 3). Of course two braces similar to said brace e might be employed, but one is usually sufficient. The brackets C are so located on the hull of the life boat, and are so extended outwardly therefrom, 95 that as shown in Figs. 1 and 2, the outer periphery of the wheel H is about in the same vertical plane as the outer rim of the adjacent gunwale of said life boat, and this arrangement is most important in that it 100 insures that no matter what may be the list of the life boat as respects the hull of the ship, the frame of the life boat can never strike against the hull of the ship so long as the wheels H and the gunwale of 105 the life boat are intact. This is an additional safe-guard against the crushing of the life boat which is not found in any devices in this art known to applicant. Said wheel H is preferably a solidly constructed 110 spoke-wheel with solid rubber tire z, which acts as a cushion to diminish the shock of

collisions against the side of the ship S. Said wheel H preferably turns on an axle *j*, which passes through suitable holes in the said braces *e*—*e*, yoke *c* and brace *d*, with a 5 nice working fit through the hub *h* of said wheel H.

It will be apparent that the described 10 construction of the wheel brackets C distributes the shocks of collisions of the wheels H over a large surface of the hull of the life boat A, and that the principal shocks 15 are directly received by the strengthening bands B—B.

It will be evident from the foregoing 20 description, that, as the boat A, which is suspended by tackle from the davits U on the ship S in any suitable manner is lowered away, the said wheels H will roll smoothly 25 down the hull of said ship S, keeping the life boat A upright, and that the said wheels H, brackets C and bands B will protect the hull of said life boat A from injury, if said life boat collides with the pitching or rolling ship.

25 Now having described my improvements, I claim as my invention.

1. The combination with the hull of a lifeboat adapted to be launched from a ship, of a plurality of strengthening bands extending substantially from the gunwale to the keel of said life boat, brackets mounted on said bands approximately at the bilge of said life boat, and adapted together with said bands to distribute shocks over a large 30 area of the said hull, and wheels mounted in said brackets and adapted to roll on the side of said ship as the said life boat is raised or lowered, substantially as described.

2. The combination with the hull of a life boat adapted to be launched from a ship, of 40 a plurality of vertical bands, one of said bands being nearer to the bow and the other nearer to the stern of said life boat, wheels, and brackets therefor mounted on said bands adjacent to the curve of the bilge of the said 45 hull, and so extended outwardly from said hull that the peripheries of said wheels are approximately in the same vertical plane as is the upper part of the said hull, substantially as described.

3. The combination with the hull of a life boat of vertical strengthening bands, and 50 wheel brackets mounted thereon and comprising a yoke fastened to said band, a lateral stay brace *d* and a longitudinal stay brace *e*, and a wheel mounted in said bracket and adapted to roll on the side of a ship, substantially as described.

4. The combination with the hull of a life boat adapted to be launched from a ship of 60 a plurality of bands, extending substantially from the gunwale to the keel, brackets mounted thereon and located below the gunwale and above the center of gravity of said lifeboat, and wheels carried by said brackets and adapted to roll down the side of the ship, substantially as described.

Signed at Brooklyn, in the county of Kings, and State of New York, this 4th day of December, A. D. 1913.

70

CHARLES W. WEILAND.
